NECKTIE RACK

Cyril Kruger, New York, N. Y.

Application August 2, 1950, Serial No. 177,193

5 Claims. (Cl. 211—96)

1

This invention relates to new and useful improvements in necktie hangers of the type disclosed in my co-pending applications Serial Nos. 169,589 filed June 22, 1950, and 174,845 filed July 20, 1950.

The racks of the co-pending applications comprise a pair of parallel bars of which one is secured on a wall and the other is movable relative thereto by means of a crank interconnecting the ends of the bars. The ties are supported by wire members pivotally engaged in both bars and having both ends projecting therefrom to form a double row of tie supports which are collapsible against the bars on movement of the latter.

One object of the invention is the provision of a parallel bar tie rack having a plurality of double rows of tie supports.

Another object of the invention is to construct the improved tie rack so that the same is positionable at any desired angle relative to a supporting wall or the like to facilitate manipulation of the parallel bars thereof and thus to facilitate the mounting or removing of ties therefrom.

Still another object of the invention is to construct the device so that the same is adapted to be manufactured economically and yet is capable of long life.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of an exemplification of the invention with the tie supports projected.

Fig. 2 is a plan view of the device with the tie supports collapsed against the bars and with the bars folded back against the supporting wall.

Fig. 3 is a side elevation of the device with the tie supports projected.

Fig. 4 is a detached side elevational view of a tie support on a larger scale than in the preceding figures.

Fig. 5 is a detached plan view of the support on the same scale as Fig. 4.

Fig. 6 is a sectional view on line 6—6 of Fig. 1, with the parts drawn to the enlarged scale of Figs. 4 and 5.

Referring now to the drawings, wherein an exemplification of the invention is illustrated, the reference numeral 10 indicates a bracket secured by screws or the equivalent on a wall or the like.

11. The bracket includes a plate which abuts the wall and a pair of vertically spaced flanges 12 between which the end of a long bar 13 is pivotally mounted on a pin 14, see Figs. 1-3. It is believed 15 evident that the pivotal mounting of bar 13 permits of the same being swung from a position wherein it is substantially parallel with the wall 11 on either side of the bracket to a position in which it is perpendicular to the wall. To facilitate such swinging the free end of bar 13 is provided with an upstanding knob or handle 15.

Arranged on either side of and slightly above the bar 13 there are bars 16 somewhat shorter than the former but parallel therewith throughout their length. The bars 16 are pivotally connected to the bar 13 each by a plurality of tie supports 17. Each tie support 17 consists of a length of stiff wire having a lower, horizontal tie supporting portion 18 and an upper horizontal tie supporting portion 20 offset laterally, see Figs. 4 and 5. The free ends 18^a and 20^a of the tie supporting portions 18 and 20 are turned up somewhat to prevent accidental disengagement of neckties therefrom. From its upper portion 20 each support member 17 has a short vertical portion 21 which extends vertically upward through a suitable hole 16^a in the appropriate bar 16, as shown in Fig. 6; and from its lower portion 18 each member has a long vertical portion 22 which extends upward through a suitable hole 13^a in bar 13. As best shown in Figs. 1, 2 and 3, the vertical portions 21 and 22 are connected by a laterally extended arcuate portion 23 which extends across the top of the bar 13 and the appropriate bar 16.

The vertical portions 22 of the tie supports 17 whose other vertical portions 21 extend through one bar 16, are interspersed along the bar 13 with those whose other vertical portions 21 extend through the other bar 16. Thus, alternate tie supports 17 are located on opposite sides of the bar 13, this, along with the offsetting of the lower and upper horizontal portions 18 and 20 of each support, preventing untidy and injurious bunching of the ties supported by the rack.

The bar 13 is made of stock which is heavier than the stock employed for making the side bars 16. This is necessary because the bar 13 supports the entire weight of the rack and ties requiring greater rigidity than the bars 16 which only support the weight of the ties positioned thereon. Furthermore, forming the bar 13 of heavier stock provides longer bearing holes for the vertical portions 22 of the tie supports 17 which vertical portions take the major portion

of the weight of the bars 16 and ties mounted thereon during all pivotal action. The longer bearing holes also serve to prevent binding of the parts during pivotal movement. The arcuate formations 23 at the top ends of the vertical portions 21 and 22 of the tie supports 17 have been chosen because they permit the width of the tie rack to be reduced to a minimum and gives a neater appearance at the top of the tie rack.

From Figs. 1, 2 and 6, it will be noted that the bearing holes 13^a in the bar 13 through which the vertical portions 22 of the tie supports 17 are extended are arranged in longitudinal lines on opposite sides of the longitudinal center of the bar 13. This is essential to provide clearance between the two rows of lower tie supporting portions 18 and prevent interference between those tie supporting portions when the rack is folded together.

The bars 16 are adapted to be moved individually lengthwise relative to the bar 13 to project the supports 17 at right angles thereto for purposes of gaining access to ties thereon, or to collapse or fold the supports thereagainst to conserve space and secure the ties thereon. It is for this purpose that the arcuate portion 23 is provided between the vertical portions 21 and 22 of each support member. To facilitate such movements a knob 24 projects vertically from that end of each bar 16 furthest from the bracket 10.

The tie supports 17 at the two ends of the bars 16 have sleeves 25 loosely mounted on their vertical portions 22. Those sleeves 25 are of a vertical extent to be disposed between the top face of the bar 13 and the points where the arcuate portions 23 continue from the top ends of the vertical portions 22, so as to hold the tie supports 17 in desired vertical positions with bar 13 to maintain the bars 16 properly elevated with relation to the bar 13. In addition, those sleeves 25 even up and smooth out the pivotal movement of the tie supports 17 on each side of a dead center improving the pivotal action of the parts. The sleeves 25 are formed of material having a width corresponding to the width of the bar 13 between the outer faces of the vertical portions 22 and the outer faces of the bar 13 so that the outer faces of the sleeves 25 will be vertically flush with the outer faces of the bar 13. Thus, when the bars 16 are moved to extend the tie supports 17 laterally from the sides of the rack, the bars will strike the outer faces of the sleeves 25, as shown in Fig. 6, limiting movement of the bars 16 once the tie racks have reached their right angularly disposed position — the sleeves 25 function as movement limiting stops for the bars 16.

The knobs 15 and 24 provide a convenient means for manipulating the bars 16 with relation to the bar 13. Applying pressure on one of the knobs 24 while gripping that knob and the knob 15 will cause the respective side of the rack to be collapsed against the bar 13. Pushing on the knob 24 will cause that side of the rack to be extended to an operative position.

The tie rack is symmetrically on either side of the mounting bracket 10, and the bracket may be mounted on either side of a closet door and the bars swung relative to the bracket into a position parallel to the closet door. On the other hand, if necessary, the tie rack can be mounted against a wall with only one side thereof being in operation.

It will be seen, therefore, that there has been

provided a necktie rack in which the tie supports are foldable or collapsible and which is foldable in its entirety against a wall or the like.

It is to be mentioned that the several components of the improved tie rack are preferably formed of plated metal, although the utilization of wood or plastic in their construction is contemplated.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A tie rack which comprises a bracket securable on a wall or the like and having a pair of horizontal flanges, a long bar having one end pivoted on said flanges, a pair of shorter bars arranged on either side of the first said bar and above the latter, all of said bars being parallel with one another, a knob at the outer end of each bar to facilitate manipulation thereof, and a plurality of double tie hangers pivotally connecting the first said bar with each of the second said bars, each said hanger comprising a stiff wire having a lower horizontal portion, an upper horizontal portion offset therefrom, a vertical portion extending upward through a hole in a second said bar from said upper horizontal portion, a vertical portion extending upward through a hole in the first said bar from said lower horizontal portion, and an arcuate portion connecting said vertical portions above the second said bar.

2. A tie rack which comprises a bracket securable on a wall or the like and having a pair of horizontal flanges, a long bar having one end pivoted on said flanges, a pair of shorter bars arranged on either side of the first said bar and above the latter, all of said bars being parallel with one another, a knob at the outer end of each bar to facilitate manipulation thereof, and a plurality of double tie hangers pivotally connecting the longer bar with each of the shorter bars, each said hanger comprising a stiff wire having a lower horizontal portion, an upper horizontal portion offset therefrom, a vertical portion extending upward through a hole in a second said bar from said upper horizontal portion, a vertical portion extending upward through a hole in the first said bar from said lower horizontal portion, and an arcuate portion connecting said vertical portions above the second said bar, whereby the several hangers pivotally connect each shorter bar with the longer bar in parallelism, movements of the shorter bars projecting the horizontal portions of the hangers or folding them against the bars.

3. A tie rack which comprises a bracket securable on a wall or the like and having a pair of horizontal flanges, a long bar having one end pivoted on said flanges, a pair of shorter bars arranged on either side of the first said bar and above the latter, all of said bars being parallel with one another, a knob at the outer end of each bar to facilitate manipulation thereof, and a plurality of double tie hangers pivotally connecting the longer bar with each of the shorter bars, each said hanger comprising a stiff wire having a lower horizontal portion, an upper horizontal portion offset therefrom, the outer ends of said horizontal portions being turned upward, a ver-

tical portion extending upward through a hole in a second said bar from said upper horizontal portion, a vertical portion extending upward through a hole in the first said bar from said lower horizontal portion, and an arcuate portion connecting said vertical portions above the second said bar.

4. A tie rack which comprises a bracket securable on a wall or the like and having a pair of horizontal flanges, a long bar having one end pivoted on said flanges, a pair of shorter bars arranged on either side of the first said bar and above the latter, all of said bars being parallel with one another, a knob at the outer end of each bar to facilitate manipulation thereof and a plurality of double tie hangers pivotally connecting the first said bar with each of the second said bars, each said hanger comprising a stiff wire having a lower horizontal portion, an upper horizontal portion offset therefrom, the outer ends of said horizontal portions being turned upward, a vertical portion extending upward through a hole in a second said bar from said upper horizontal portion, a vertical portion extending upward through a hole in the first said bar from said lower horizontal portion, and an arcuate portion connecting said vertical portions above the second said bar, whereby the several hangers pivotally connect each shorter bar with the longer bar in parallelism, movements of the shorter bar projecting the horizontal portions of the hangers or folding them against the bars.

5. A tie rack which comprises a bracket securable on a wall or the like and having a pair of horizontal flanges, a long bar having one end pivoted on said flanges, a pair of shorter bars arranged on either side of the first said bar and above the latter, all of said bars being parallel

with one another, a knob at the outer end of each bar to facilitate manipulation thereof, and a plurality of double tie hangers pivotally connecting the first said bar with each of the second said bars, each said hanger comprising a stiff wire having a lower horizontal portion, an upper horizontal portion offset therefrom, the outer ends of said horizontal portions being turned upward, a vertical portion extending upward through a hole in a second said bar from said upper horizontal portion, a vertical portion extending upward through a hole in the first said bar from said lower horizontal portion, and an arcuate portion connecting said vertical portions above the second said bar, whereby the several hangers pivotally connect each shorter bar with the longer bar in parallelism, movements of the shorter bar projecting the horizontal portions of the hangers or folding them against the bars, and a sleeve embracing the last said vertical portion of two or more of the hangers connected to said longer bar, said shorter bars contacting said sleeves in its movements.
